RESETTABLE CIRCUIT BREAKER

René Carle, Brooklyn, N. Y., assignor, by mesne assignments, to Thermo Electric Fuse Corp., New York, N. Y., a corporation of New York

Application April 6, 1948, Serial No. 19,279

13 Claims. (Cl. 200—116)

1

This invention relates to resettable circuit-breakers, particularly although not exclusively of the plug form type adapted for connection in ordinary line sockets.

It is primarily within the contemplation of my invention to provide a device of the above-mentioned category containing certain important safety features in addition to the usual safeguard against injurious effects caused by short circuits and current overloads. More specifically, it is an object of my invention to provide, among others, the following two features: (1) an arrangement of coacting electrical contactors separate and independent from a thermal-responsive latching arrangement, and (2) an arrangement for preventing the coacting electrical contactors from being held in circuit-closing condition, except when the thermal-responsive element is in its normal and non-deformed condition.

It is also an object of this invention to provide an additional safety feature in circuit-breakers of the above-mentioned category whereby there are no exposed openings or manually operable elements when the circuit-breaker is in position and when current is flowing therethrough, so that the danger of accidental contact with a live conductor is eliminated.

Although many attempts have been made to provide circuit-breakers and similar devices with resettable features, including certain of the features above-mentioned, the devices have generally been intricate, delicate in structure, easily upset, and difficult and hence costly to manufacture. It is accordingly an important object of this invention to eliminate the said shortcomings of other devices in the above-mentioned category by providing a simple, rugged, as well as easily operable device, capable of performing the aforesaid functions and possessing the safety features above-mentioned.

Other objects, features and advantages will appear from the drawings and the description hereinafter given.

Referring to the drawings:

Figure 1 is a vertical section of the circuit-breaker of my invention shown in its normal or circuit-closing condition.

Figure 2 is a section of Fig. 1 taken along line 2—2.

Figure 3 is a view like Fig. 1, showing the thermal element in its retracted position and the device in its circuit-opening position.

Figure 4 is a longitudinal section of Fig. 3 taken along line 4—4.

2

Figure 5 is a top view of the inner shell member and both contact-carrying arms, looking downwardly from line 5—5, the outer shell having been removed.

5 Figure 6 is a fragmentary schematic section of the device showing the parts in the normal circuit-closing position of Fig. 1.

Figure 7 is a view like Fig. 6, showing the device in its circuit-opening position, like that of 10 Fig. 3.

15 Figure 8 is a view similar to Fig. 7, but showing the cooled bi-metallic element partially curved and restrained by the inner shell wall from assuming its normal curved position shown by dot-dash lines; and

Figure 9 is a view like Fig. 8, showing the device in the process of being reset, the upper contact element having been moved from the dot-dash position to the uppermost position shown.

20 In the preferred form of my invention illustrated in the drawings, the device is shown in the form of a plug fuse consisting of the outer (or upper) shell 10, which may be made of plastic, "Pyrex" glass or other insulator, the inner (or lower) plug shell 11, which may also be made of suitable insulating material such as hot or cold molded thermo-setting plastic, the outer brass screw shell 12 constituting one fixed contact terminal, the base contact terminal 13 extending through the lower wall 11a of shell 11, the thermal-responsive bi-metallic strip 14 electrically and mechanically connected to the said terminal 13, the lateral spring branch (or lower contact arm) 15 attached to the distal end 16 of the strip 14 and carrying the insulator block 17 at the bottom thereof and the electrical contact element 18 on the upper surface thereof; the upper spring contact arm 19 electrically connected to shell 12 and carrying on the undersurface thereof the contact 20, and the reset pin 21 composed of insulating material and slidably movable within channel 22 of inner shell 11 and against the adjacent surface of the outer shell 10.

The said outer shell 10 has a flat flanged outer wall 23, this wall being exposed to view when the plug is operably in place, the wall in the preferred form illustrated being solid and containing no openings whatsoever. The cylindrical wall 24 of shell 10 surrounds the cylindrical wall 25 of the inner shell 11 which extends into the hollow interior of shell 10, said cylindrical wall 25 being preferably in slidable engagement with the interior surface of said wall 24. The laterally extending annular wall 26 of the inner shell 11 serves as a stop for the inner annular

edge 27 of wall 24, thereby establishing the assembled relation between the outer and inner shells 10 and 11, respectively. The said brass shell 13 is in threaded engagement with the outer surface of wall 24 of shell 10, and contains the annular base 28 underlying and in engagement with the lower surface of said wall 26, the arrangement hence serving to maintain the said inner and outer shells 10 and 11 in coactive assembled relation.

The said spring arm 19, which may be made of beryllium copper or some other suitable resilient conductor, extends from its free end transversely within the inner cavity of the device, is then sharply bent to form the longitudinally or downwardly extending portion 29 disposed within recess 40 of wall 25 and against the inner surface of wall 24, and then extends between the inner edge 27 of wall 24 and the abutting surface of wall 26 and upwardly along outer surface of wall 24 into preferably soldered engagement with screw shell 12. The arrangement is hence such that the said spring arm 19 is physically held in position by having extended portions thereof clamped between the said inner and outer shells 10 and 11.

The bi-metallic strip 14 has its upper portion 30 normally curved inwardly towards the reset pin 21, it being so designed that when an excess amount of current passes therethrough, it will straighten up, bending away from its said inclination towards the said reset pin. The reset pin 21 contains an intermediate ledge 31 disposed inwardly towards the cavity of the device, said ledge being adapted to engage the extended portion 32 of spring branch 15, in a manner to be hereinafter set forth. The reset pin also contains the upper ledge or terminal 33 with which the extended portion 34 of spring arm 19 is in constant yieldable engagement. The lower portion 35 of the reset pin extends downwardly below the recess 41 in the annular wall 26 and beyond the annular base 28 of the screw shell 20, the shoulder 36 thereof being abuttable with the inner surface of said base 28 to limit the downward movement of the reset pin. The said protruding portion 35 of the reset pin is manually engageable to impart a longitudinal sliding movement thereto, for purposes to be hereinafter set forth.

In the normal circuit-closing position of the device, contacts 18 and 20 are in engagement, and the insulating block 17 rests upon the shelf 37 recessed downwardly from the upper edge 42 of the inner shell 11. In this condition the electrical path is through the base contact terminal 13, the bi-metallic strip 14, the spring branch 15, the two contacts 18 and 20, the spring arm 19 and portion 29 thereof to the outer brass screw shell 12.

Upon a current overload condition, the said bi-metallic strip 14 will straighten out, causing upper portion 30 thereof to move to the left, away from the reset pin 21, thereby retracting the insulating block 17 from its position on shelf 37, to cause said block to clear said shelf and the entire spring branch 15 to move downwardly. Since the spring branch 15 exerts a normal pressure downwardly, this retraction will cause a downward clicking action of the insulating block to the position shown in Fig. 7. In this position the contacts 18 and 20 have been separated, thereby breaking the circuit. However, due to the downward urging of spring arm 19, the reset pin will also be slidably moved downwardly until the said shoulder 36 engages the base 28. In this

position, the extension 32 of spring branch 15 is disposed above the intermediate ledge 31; and since the outer extension 34 of spring arm 19 is held against downward movement by the terminal 33 of the reset pin, the contacts 18 and 20 are maintained in a separated condition. It is important that when the device is in its tripped condition, as shown in Fig. 7, that ledge 31 be disposed below the said extension 32, the latter resting upon the said shelf 37 of the inner shell 11.

To reset the device into circuit-closing condition, the reset pin is pushed upwardly, whereupon the following action takes place in the sequence indicated: the terminal 33 of the reset pin first lifts extension 34, thereby raising the entire spring arm 19 to the position shown in Fig. 9; and in the course of this upward movement (after terminal 33 has engaged extension 34), the ledge 31 engages the extension 32 of the spring branch 15, causing it to move upwardly. However, since, upon a cooling of the bi-metallic strip 14, portion 30 thereof has again assumed its normal curved shape, the raising of branch 15 beyond the level of shelf 37 will snap the insulating block 17 over and in pressing engagement with said shelf. This action is enhanced by the fact that the curvature of portion 30 and its extension to a point above shelf 37 causes a forward and downward pressure thereupon. Thereafter, upon a release of the reset pin 21, and under the spring action of contact arm 19, contact 20 will engage contact 18, and will further press the insulating block 17 into engagement with said shelf 37. In this position the device is in circuit-closing condition, with the two contacts 18 and 20 in firm yieldable engagement.

It is to be noted that the arrangement above described makes it impossible to so manipulate the reset pin as to keep the two contacts 18 and 20 in engagement unless the insulating block 17 rests on the shelf 27, and the device is in its intended "trippable" position. This must be so since before the intermediate ledge 31 can reach the extension 32 and lift spring branch 15, it must first move the spring arm 19 upwardly, away from the position at which the two contacts 18 and 20 can come into engagement. In other words, when the terminal 33 and the ledge 31 of the reset pin are in simultaneous engagement with the extensions 34 and 32, respectively, finger 38 (the portion of the reset pin between ledge 31 and terminal 33) is deliberately made sufficiently long to keep the said two contacts 18 and 20 separated.

It should be further noted that since the reset pin 21 is located at the inner portion of the circuit-breaker, it becomes necessary to first remove the circuit-breaker from the wall receptacle in which it is housed in order to reset it. This provides a safety feature in that the only time a person need handle the device (except when removing the entire device from the receptacle) is when it is remote from any source of current.

It will be observed that the various objectives above mentioned, particularly the physical separation of the thermal-responsive latching elements from the electrical contact, and the resetting safety feature above described, are attained in a device having relatively few moving parts, and without the use of a combination of cams, levers and links such as are frequently found in other devices of this category.

In the above description, the invention has been disclosed merely by way of example and

in preferred manner; but obviously many variations and modifications may be made therein which will still be comprised within its spirit. It is to be understood, therefore, that the invention is not limited to any specific form or manner of practicing same, except insofar as such limitations are specified in the appended claims.

I claim:

1. In a resettable circuit breaker, a hollow insulating body portion, two fixed electrically separated electrical terminals on the outer surface of said body portion, an internal shelf within said body portion, a reset pin slidably movable within said body portion and having a manually engageable portion extending outwardly therefrom, said pin having an intermediate ledge adjacent said shelf and an upper ledge disposed within said body portion, a thermal-responsive strip connected to one of said terminals and being normally bent towards said reset pin and being adapted to bend away therefrom under predetermined current overload conditions, a spring conductor branch extending from said strip and having on the undersurface thereof an insulating block adapted to rest upon said shelf when the strip is in said normally bent position and retracted therefrom when the strip is in its said overload condition, said branch containing an extension beyond said insulating block adapted to rest upon said shelf when the block is in said retracted position, the upper surface of said branch containing an electrical contact, a spring conductor arm electrically connected to the other of said terminals and positioned above said branch and containing on its undersurface a second electrical contact engageable with said first-mentioned contact when said insulating block is disposed on said shelf, said arm also containing an extension beyond its contact in yieldable pressing engagement with said upper ledge of the reset pin, said contacts being separated when the spring branch extension is resting upon the said shelf, the said intermediate ledge being engageable with the said spring branch extension upon an upward movement of the reset pin to cause an operative resetting elevation of the said spring branch, the reset pin being movable under the action of said spring arm to a predetermined lower position when the block is in said retracted position.

2. In a resettable circuit breaker, the combination according to claim 1, the intermediate ledge of the reset pin being below and out of engagement with the said spring branch extension when the said reset pin is in its said predetermined lower position.

3. In a resettable circuit breaker, the combination according to claim 1, further provided with a stop member to limit the downward movement of the reset pin to said predetermined lower position, the intermediate ledge of the reset pin being below the said shelf when it is in said lower position.

4. In a resettable circuit breaker, the combination according to claim 3, one of said fixed terminals being a screw shell in threaded engagement with the outer surface of said body portion, said screw shell containing an inwardly bent annular base engageable with the reset pin and constituting the said stop member.

5. In a resettable circuit breaker, the combination according to claim 4, the other of said fixed terminals being disposed in the lower part of the said body portion, the said thermal responsive strip being attached to said last-men-

tioned terminal, the said spring branch being connected to the distal end of said strip.

6. In a resettable circuit breaker, the combination according to claim 1, the said normally bent portion of the thermal-responsive strip carrying the said spring branch and being disposed above the said shelf.

7. In a resettable circuit breaker, the combination according to claim 1, the said body portion consisting of an outer shell and an inner shell in telescopic assembled relation, the said spring arm having an extension clamped between said inner and outer shells.

8. In a resettable circuit breaker, the combination according to claim 7, the said inner shell containing an annular wall engageable with the adjacent portion of the outer shell, said annular wall containing therein a recess, the said reset pin having a portion thereof extending through said recess.

9. In a resettable circuit breaker, the combination according to claim 1, the said body portion consisting of an outer shell and an inner shell in telescopic assembled relation, the said spring arm having an extension clamped between said inner and outer shells, the said shelf being a depressed portion of the upper edge of said inner shell.

10. In a resettable circuit breaker, the combination according to claim 1, the said reset pin being slidably disposed within an inner recess in the body portion, the upper terminal of said reset pin constituting said upper ledge.

11. In a resettable circuit breaker, the combination according to claim 1, the said body portion consisting of an outer shell and an inner shell in telescopic assembled relation, the said spring arm having an extension clamped between said inner and outer shells, said outer shell containing a solid top wall, the said reset pin extending downwardly beyond the bottom edge of the outer shell.

12. In a resettable circuit breaker, two adjacent movable contact arms bearing abuttable contacts, and a movable reset pin, said pin containing two ledges each engageable with one of said arms, the distance between said ledges being such that when both ledges are in simultaneous engagement with both arms, the contacts will be out of engagement; one of said arms being yieldably urged towards the other to bring said contacts into engagement, said reset pin being movable to urge one of the arms engaged thereby away from the other, whereby said contacts will be separated, said circuit breaker being further provided with a thermal-responsive element, one of said arms being connected to said element, a latch holding said arms with their said contacts in engagement, said thermal-responsive element being bendable under predetermined current overload conditions to disengage said latch from its said holding position, and spring means urging said thermal-connected arm away from the other arm.

13. In a resettable circuit breaker, one upper and one lower contact-bearing arm, mutually engageable contacts on said arms, and a reset pin movable between upper and lower limiting positions, said pin containing two ledges, one above the other, the upper ledge being engageable with the upper arm and the lower ledge with the lower arm, the distance between said ledges being such that when both ledges are in simultaneous engagement with both arms, the contacts will be out

of engagement, the upper of said arms being yieldably urged towards the lower to bring said contacts into engagement, said reset pin being movable towards its said upper limiting position whereby it will elevate the arm engaged by the upper ledge and separate the upper contact from the lower contact, said lower arm being movable between an upper position where the contacts are in engagement to a lower position where they are out of engagement, the said lower ledge being adapted to engage said lower arm to elevate it to the said contact-engaging position, the upper arm yieldably bearing downwardly against the upper ledge of the reset pin to urge it towards its said lower limiting position, said circuit breaker being further provided with a thermal-responsive element, the lower of said arms being connected to said element, a latch holding said arms with their said contacts in engage-

ment, said thermal-responsive element being bendable under predetermined current overload conditions to disengage said latch from its said holding position, and spring means urging said thermal-responsive-connected arm away from the other arm.

5 RENÉ CARLE.
